UNITED STATES PATENT OFFICE.

OLOF NELSON, OF ATTLEBORO, MASSACHUSETTS, ASSIGNOR TO THE ROBBINS COMPANY, OF ATTLEBORO, MASSACHUSETTS, A CORPORATION OF RHODE ISLAND.

NAME-PLATE ATTACHMENT.

1,405,547.

Specification of Letters Patent. Patented Feb. 7, 1922.

Application filed October 19, 1921. Serial No. 508,677.

To all whom it may concern:

Be it known that I, OLOF NELSON, a citizen of the United States, residing at Attleboro, in the county of Bristol and State of Massachusetts, have invented certain new and useful Improvements in Name-Plate Attachments, of which the following is a specification.

My invention is an improved means for connecting a name or emblem plate or the like to any desired supporting surface. The immediate and particular object I have in view is to secure a name or emblem plate upon the shell or cover of the radiator of an automobile. This radiator shell is in effect a cover for the radiator proper, which is a cellular or tubular element, through which the heated water from the water jackets of the motor cylinders is passed to dissipate heat units to the air, and the shell fits the radiator closely, so that it is difficult or impossible to insert hands or tools between the shell and the radiator or to get at the inner surfaces of the shell without removing the shell from the radiator.

In the drawings:

Figure 1 is a front or plan view of a portion of a radiator cover or other supporting surface, slotted to receive a name or emblem plate;

Figure 2 is a section on line 2—2 of Figure 1;

Figure 3 is a rear view of an emblem plate, carrying the connecting device secured thereto;

Figure 4 is a central section of an emblem plate attached to a radiator cover;

Figure 5 is a perspective view of the attaching device separate from the name plate;

Figure 6 is a cross-sectional view on line 6—6 of Figure 5.

My connector is made in two parts and the engagement between the two parts is a friction locking engagement. The engagement and locking is accomplished by the interaction of the parts themselves, when they are brought together. The result is that the engagement is effected with the utmost simplicity and security so that the vibration of the machine, in use has no effect whatever upon the union of the parts which retain their engagement until force is designedly applied between the parts to separate them.

One element of my connecting device is

shown in Figures 5 and 6. It consists preferably of a metal tube, *a*, having a flattened side *a'* and split at *a''*, along the side opposite to the flattened side. This tube is secured along its flattened side by soldering, brazing or other means, to the back of the name or emblem plate A.

In another plate or preferably in the substance of the front of the metal radiator shell B, at the desired point of attachment, I punch a slot, *b*, of a length very slightly greater than the length of the tube, *a*, and having in-turned lips, *b'* (see Figures 1 and 2). The free ends of the lips *b'* slant toward each other and are set and spaced apart a designed distance in the punching operation. The distance designed will have relation to the cross-sectional size of the tube, *a*, with which, as will be presently explained, the lips *b'* cooperate in use. It will be observed (see Fig. 6) that the edges *a''* of the split tube are separated.

In applying the name or emblem plate to the supporting surface, for example, a motor car radiator shell, the tube, *a*, secured to the emblem plate (see Fig. 3) is inserted in the slot, *b*, and is pressed into the slot. The metallic tube, being wider than the distance between the free edge of the lips, *b'*, wedges the lips *b'* apart and is itself, by the resistance of the lips to this wedging section, distorted, the edges *a''*, of the split in the tube being forced to approach each other as the edges of the lips pass onto the widest part of the sides of the tube, when the inherent resilience of the two connector parts causes the opposed surfaces to be engaged with a powerful resilient friction grip.

This operation is most easily performed, for the wedging action multiplies the force applied in pushing the emblem plate to position and reacts to the force employed, (which is perpendicular to the surface of the radiator shell) substantially in a direction parallel to the surface of the radiator shell, which is not therefore pressed inward in any damaging manner.

The attached name plate is held tightly and securely, without rattle or possibility of working loose, and cannot rotate nor change its position longitudinally or laterally, unless force is applied designedly to break the frictional grip of the connector elements, while the force required to establish the frictional grip, owing to the shape and organi-

zation of the parts, is in a direction having no tendency to dent or damage the radiator shell.

I have described above the preferred embodiment of my invention in which both elements of the attaching device have free edges or lips, capable of being forced apart or together. An engagement may be effected however where only one of the parts 10 has free edges or lips, and such a device, while not so effective, would be within my invention.

I claim:

1. The attaching device above described, 15 consisting of a tubular wedge-member and

a plate having opposed free lips on either side of a slot therein, to receive the wedge-member between the lips.

2. The attaching device above described, 20 consisting of a slotted tubular wedge-member and a plate slotted to receive the slotted wedge-member.

3. The attaching device above described, 25 consisting of a slotted, tubular wedge-member and a plate having opposed free lips on either side of a slot therein, to receive the slotted wedge-member.

Signed at Attleboro, Massachusetts, this fifteenth day of October, 1921.

OLOF NELSON.
